UNITED STATES PATENT OFFICE.

GEORGE L. MANSFIELD, OF CHICAGO, ILLINOIS.

COMBINED DERAILER AND RERAILER.

SPECIFICATION forming part of Letters Patent No. 758,994, dated May 3, 1904.

Application filed July 6, 1903. Serial No. 164,409. (No model.)

To all whom it may concern:

Be it known that I, GEORGE L. MANSFIELD, a resident of the city of Chicago, county of Cook, and State of Illinois, have invented a certain new and useful and Improved Combined Derailer and Rerailer, of which the following is a specification.

My invention relates to means for derailing cars or trains that have not the right of way upon railroads and also relates to means for rerailing cars or trains that have been derailed.

Derailers of the class to which this invention belongs are usually provided at the ends of side tracks, their purpose being to derail cars which from accidental causes may start toward the main track. To keep such a moving car from passing out through the switch and onto the main track, where it might collide with a train on the main track, it is necessary to derail the car before it reaches the main track, and when the car has thus been derailed it is desirable that it shall be replaced upon the track as quickly as possible.

To this end my invention consists, primarily, in a rerailer or replacing-frog that is placed alongside of the railroad-rail and is adapted to be moved over the same into position to guide the wheels of the derailed car upward and onto the track-rail.

My invention particularly consists in a combined derailing and rerailing frog or switch that is movable toward and from the track-rail and which when in position is adapted to either displace or replace the car-wheels that pass over it, suitable means being provided for operating the frog or switch to position the same upon the rail or remove it therefrom.

My invention also consists in the combination of a derailing frog or switch with the slide-guides therefor, which are fixed near the track-rail, and means for sliding the frog thereon, and, further, my invention consists in various details of construction and in combinations of parts, all as hereinafter described, and particularly pointed out in the claims.

My invention will be more readily understood by reference to the accompanying drawings, in which—

Figure 1 is a plan view of a combined derailer and rerailer embodying my invention.

Fig. 2 is a side view thereof, and Fig. 3 is an end view of the same.

As shown in the drawings, 2 represents the track-rail, and 3 the railroad-ties.

4 are tie-plates that are spiked to the ties and which are provided with the integral horizontal guides 5. These guides are parallel and are perpendicular to the track-rail. The tops of the guides 5 preferably rise to the height of the track-rail and serve to guide the plate or frog 6. Said plate is provided on its under side with the T-guides 7, that receive the parallel guides 5 in the parts 7, which contain the T-slots and are preferably integral with the plate 6 and have underhanging parts 7', which serve to hold the plate on the guides 5. The guides 5 are preferably recessed to reduce the friction between the parts. For operating the plate 6 I employ a rocking shaft 8, that is held in the lugs 9, which are preferably integral with the guide-plates 4. This shaft is operated by means of the arm 10, which is connected with a suitable lever or to the nearest track-switch stand. The plate 6 is provided with depending lugs or webs 11, and these contain the pins 12, by which the connection is made with the operating-arms 13 on the shaft 8. Said arms, as shown, are provided with slots 14, and when the shaft 8 is rocked the plate 6 will be moved either toward or from the rail 2.

15 represents the slot or recess provided in the under part of the plate 6 to permit the swinging of the arm 13 beneath it. The shoulders 16 on the lugs or ribs 11 strike the side of the rail when the plate is moved inwardly and serve as stops for the plate. The plate or frog 6 lies diagonally on the rail when resting on the same and is provided with a diagonal wheel-flange groove 17, which serves to guide the car-wheels either off of or onto the rail, according to the direction in which the car is moved over the device. This groove lies between the inclined or diagonal ribs 18 and 19, that are integral with the plate 6. The rib 18 ends in an abrupt wedge or incline 20 above the rail and is sufficiently high to lift the tread of a car-wheel rolling upon it and prevent the flange of the wheel from striking the plate 6 at the bottom of the groove. From

the high point the rib 18 slopes downwardly to the top level. A car-wheel rolling thereon is moved laterally by wedging engagement with the opposite rib 19. Thus the weight of the 5 car is always carried directly above or outside the rail. The outer end of the rib 19 terminates above the outer side of the rail, and when a wheel has been taken into the groove of the derailler its continued movement will project 10 it therefrom and off of the rail. The bottom of the groove 17 drops away suddenly at that end of the frog which is outside of the rail, affording a steep incline 17', defined by the sharply-inclined end 18' of the rib 18. At 15 the bottom of this incline the frog has a foot 21, that is adapted to slide on a plate 22, provided on the wide tie 3. The bottom of the foot is ribbed, as shown, to minimize the friction between the same and the tie-plate 22.

20 The cars that get loose while standing on a side track usually encounter the derailler while moving at a low speed, with the result that they are stopped as soon as the first truck of the first car is derailed, the wheels thereof 25 becoming embedded in the road-bed. Derailments are frequently of a more serious character; but the greater number occur and result as above stated, and in such cases the derailed truck will be found to lie with its wheels 30 close to the track-rails. Under such circumstances and where my device is employed it is only necessary to couple the locomotive to the car or train and draw it back onto the track, the outer wheels of the truck being 35 taken up by the quick incline 17' of the frog and forced inwardly by the rib 18 thereof while rolling over the frog. A stone or plank used at the opposite rail will lift the opposite truck-wheels at such times. The weight of 40 the car at the moment that a truck-wheel strikes the quick rerailing-incline of the frog is carried by the foot 21, and the friction between the foot and the plate 22 is sufficient to prevent the forcing out of the frog by wedging 45 action of the opposite wheels against the opposite track-rail. On the other hand, if a car enters the track behind a derailler the first truck-wheel that strikes the derailler will either wedge it off the rail or ride over the 50 derailler and no part will be damaged.

The advantages of my device are as follows: It not only provides for the derailment of a car, but also provides for the immediate rerailment thereof. It is a positive derailler and 55 a positive rerailer. In rerailing, the device may set out from the rail and will be drawn toward the rail by the lateral pull of the car. The device is positively held against longitudinal movement on the rail and is so constructed that the wedging action of the car-wheels when passing over the device in either direction tends to hold the device against and on the rail. The device has full latitude of movement, and when removed from the rail 60 there is no danger of its being struck by any

of the parts of a car-truck. Further, the device is composed of few parts, all of which are practically exposed, so that they can be easily inspected, cleaned, and lubricated.

As numerous modifications of my invention 70 will readily suggest themselves to one skilled in the art, I do not confine the same to the specific constructions herein shown and described.

Having thus described my invention, I claim 75 as new and desire to secure by Letters Patent—

1. The combined derailler and rerailer comprising the plate to lie upon a rail and having a diagonal groove to guide a wheel from either side of such rail to the other side thereof, sub- 80 stantially as described.

2. The combined derailler and rerailer comprising the plate containing a diagonal groove in its upper surface, said groove being sharply inclined at one end of the plate, and a mechanism for moving said plate, as and for the 85 purpose specified.

3. The combined derailler and rerailer, comprising the plate provided with horizontal guides, for movement toward and from a rail 90 and having a diagonal groove in its upper surface, which groove is downwardly inclined at the end of the plate, substantially as described.

4. The combined derailler and rerailer comprising the plate having horizontal and vertical portions, the latter being inclined and said plate being provided with the horizontal diagonal groove rib on one edge and with the diagonal and downwardly-inclined groove rib on the outer edge, substantially as described. 95

5. The combination, with the rail, of the plate to lie thereon and containing a diagonal groove, the horizontal guides provided upon said plate, the tie-plates and the raised guides thereon upon which said plate is slidable, sub- 100 stantially as described.

6. The combination, with the rail, of the plate containing the diagonal groove and provided with a lifting block or rib, the horizontal guides provided on the under side of said plate, the tie-plates, the guides thereon, a rocking shaft and arms thereon for operating the grooved plate, substantially as described. 110

7. The combination, with the rail and ties, of the tie-plates, the raised guides upon said tie-plates, the derailler-plate slidably held on said guides, the rocking shaft journaled in said tie-plates and the operating-arms, having slot-and-pin connections with said derailler-plate, substantially as described. 115

8. The combination, of the rail with the derailler and rerailer plate containing the diagonal groove and provided with the foot, from which said groove leads upwardly, and means for moving said plate onto or away from said rail, substantially as described. 125

9. The combination, of the rail and the ties with the plate, slideable horizontally to and away from said rail, the diagonal rib 19 on said plate, and the diagonal deflecting and lift- 130

ing rib 18 also on said plate and descending to the tie at one end of the plate, as and for the purpose specified.

10. The combination, of the rail and ties, with the derailing and rerailing plate provided with the diagonal groove and having the depressed end overhanging the side of the rail and provided with a foot slidable on the tie, substantially as described.

11. The combination of the rail, with the plate 6 containing the diagonal groove and provided with the horizontal guide portions 7, the tie-plates provided with guides 5 and means for sliding said plate, substantially as described.

12. The combination, of the tie-plates provided with horizontal guides 5, with the plate 6 having a diagonal groove and having transverse guide portions embracing said guides 5 and means for sliding said plates on said guides, substantially as described.

13. The combination, of the tie-plate, with the plate 6 containing a diagonal groove and slidable on said tie-plates the bearings pro-

vided on said tie-plates the rocking shaft there- 25 in, the arms on said shaft provided with slots and the depending lugs on said plate 6 provided pins engaging said arms, substantially as described.

14. The combination of the rail and the ties 30 with the tie-plates 4 provided with the raised horizontal guides 5, the plate 6 provided with the diagonal groove and the ribs 18 and 19, said groove being inclined at the end of the plate 6, and having the sliding foot beneath its 35 inclined end and also having horizontal guide-slots that receive said guides 5, and, means for sliding the plate 6 upon said guides, substantially as described.

In testimony whereof I have hereunto set 40 my hand, this 23d day of November, 1902, at Chicago, Cook county, Illinois, in the presence of two witnesses.

GEORGE L. MANSFIELD.
